CLAIM

The ornamental design for a tissue dispenser, as shown and described.

DESCRIPTION

FIG. 1 is a top, front, left-side, perspective view of a tissue dispenser;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an alternate top, front, left-side, perspective view thereof, shown in a state of use with an environmental tissue. The broken lines in the figures are for the purpose of illustrating portions of the tissue dispenser and form no part of the claimed design. The environmental tissue in FIG. 8, shown in broken lines, forms no part of the claimed design.

1 Claim, 5 Drawing Sheets
